SNAP ACTING DEVICE

Lyndon W. Burch, Pelham, N. Y., assignor to The
Wilcolator Company, Newark, N. J., a corpora-
tion of Delaware

Application October 31, 1939, Serial No. 302,124

4 Claims.

(Cl. 297—8)

This invention relates to snap acting devices and more particularly to a novel device of this type which includes a dished snap element operable to produce a snap action at one end or at both ends and in which the snap element and its actuating means may be included in a unitary and compact assembly. The new device is of simple construction and may be made at low cost.

One feature of the present invention resides in the provision of a novel snap mechanism in which the snap element is made from a sheet of spring metal having a dished shape and is arranged to provide a snap movement at one end or at both ends when actuated.

According to the invention, I provide abutment means engaging the convex face of the element between its ends, and abutment means engaging the concave face outwardly from the first abutment means and on opposite sides of the longitudinal axis of the element. The two abutment means are movable relatively toward each other to reduce the curvature of the snap element along its transverse axis, and when this curvature is reduced to the extent that the snap element becomes unstable, the latter snaps to a position of opposite curvature whereby its ends move quickly in a direction generally normal to the surface of the element. If desired, the snap element may be made self-recovering by forming it with an accentuated curvature or permanent strain along one axis so that it tends to return to an initial position under the action of internal stresses set up in the element due to a reversal of this curvature. Thus, when the two pairs of abutments move relatively away from each other to release the pressure on the snap element, the latter snaps back to its initial position. Alternatively, the device may be provided with separate biasing means acting to urge the snap element to its initial position, or the abutment means may be positively connected to the snap element to effect its movement in both directions.

Another feature of the invention resides in the provision of a novel snap action mechanism including a double-ended snap element operable by a thermostat through an adjustable connection, all of the parts being included in a unitary assembly. In one form of the mechanism, the snap element is seated on one side of a supporting member and is engaged on its convex side by a pressure plate. The ends of the pressure plate may be offset to support the ends of a bimetallic compensator, the pressure plate and com-

5 pensator being held in position by a retainer secured to the supporting member. Preferably, an adjustment rod operable to exert a pressure on the compensator and pressure plate extends through these members and through openings in the snap element and the supporting member, and the end of the rod has a threaded connection with a member which is movable by thermo-responsive means secured to the supporting member. The thermo-responsive means operates through the adjustment rod, compensator and pressure plate to vary the pressure on the snap element and thereby cause actuation of the latter. By adjusting the rod, the temperature at which the thermo-responsive means actuates the snap element may be varied.

These and other features of the invention may be better understood by reference to the following detailed description taken in conjunction with the accompanying drawing, in which

Fig. 1 is a transverse sectional view of one form of the new snap mechanism, showing the snap element in its flexed position;

Fig. 2 is a similar view showing the snap element in its normal position, parts of the mechanism being shown in elevation;

Fig. 3 is a longitudinal elevational view of part of the mechanism shown in Fig. 1, with the snap element in its flexed position;

Fig. 4 is a view similar to Fig. 3 showing the snap element in its normal position;

Fig. 5 is a plan view of the snap element shown in Figs. 1 to 4, inclusive;

Figs. 6 and 7 are longitudinal and transverse sectional views, respectively, of the snap element;

Fig. 8 is a sectional view on the line 8—8 in Fig. 5;

Figs. 9 and 10 are detail views of different parts of the device shown in Figs. 1 to 4, inclusive, and

Fig. 11 is a plan view of a modified form of the snap element.

Referring to the drawing, the snap mechanism illustrated comprises a snap element 20 made from a sheet of spring metal which, as shown, is generally rectangular in form. Radiating from the central portion of the sheet toward the corners thereof are slots 21 terminating a short distance inwardly from the corners. The metal between the outer end of each slot and the adjacent corner is crimped, as shown at 22, so that the outer portion of the sheet is drawn in or gathered. As a result, the effective perimeter of the sheet is re-

duced and the sheet is caused to assume a dished shape. Preferably, the lengthwise curvature of the sheet is increased beyond that resulting from the gathering of the metal at the corners, so that the sheet is subjected to a permanent strain tending to return it to the position shown in Figs. 2 and 6 when it is flexed to a position of opposite curvature, as will be described in greater detail presently.

The snap element forms a part of the subject matter of my copending application, No. 325,979, filed Mar. 26, 1940, which is a continuation-in-part of the present application.

The snap element may be flexed by any suitable means to force it to a position of opposite curvature. In the drawing, I have shown a preferred form of flexing means comprising a supporting plate 23 on which a pair of headed pins 24 are mounted, the pins extending upwardly through openings 25 located near the sides of the snap element on the transverse axis thereof. Thus, the heads of the pins 24 act as seats engaging the normally concave side of the snap element, and the shanks of the pins serve to locate the snap element relative to the supporting plate. On top of the snap element is a pressure plate 26 having spaced abutments 27 engaging the normally convex side of the snap element inwardly from the pins 24. The pressure plate is formed with openings 28 through which the shanks of the pins extend, and surrounding the openings are bosses 29 adapted to be engaged by the snap element. The ends of the pressure plate are offset and reduced, as shown at 30, and mounted on these ends is a bimetallic compensator 31 which is likewise provided with reduced ends 31' seated on the ends of the pressure plate. The compensator is held in position on the pressure plate by a U-shaped retaining member 32 having slots in the legs thereof for receiving the reduced ends of the compensator and pressure plate. Lugs 33 project from the supporting plate through openings in the legs of the retaining member and serve to secure the latter to the supporting plate.

An adjustment rod 34 extends through openings in the retainer 32 and the compensator and through aligned openings in the pressure plate, the snap element and the supporting plate, the rod being threaded at its lower end into a headed pin 35. A spring 36 is coiled around the pin 35 between the head thereof and the supporting plate 33, and the spring urges the pin and rod downwardly so as to hold a shoulder 37 on the rod in engagement with the retaining member 32.

The pin 35 is movable by a thermo-responsive assembly mounted on the side of the supporting plate 23 remote from the snap element. This assembly, as shown, comprises a cup-shaped member 38 secured at its open end to the supporting plate and containing a metallic bellows 39 sealed at its open end to an annulus 40, whereby the bellows, the annulus and the cup-shaped member define an expansible and contractible chamber 41. A capillary tube 42 leads from this chamber to a bulb, not shown, and the bulb, tube and chamber may be filled with a thermo-responsive liquid, such as chlorinated diphenyl, so that the bellows will expand and contract as a result of thermal expansion and contraction of the liquid in the bulb.

In the normal position of the parts shown in Figs. 2 and 4, the pressure exerted on the snap element by the pressure plate 26 is relatively small so that the snap element assumes its ini-

tial position in which its ends are depressed. When the rod 34 is rotated to screw it into the pin 35, the head of the latter is raised from the end of the bellows against the action of spring 36. At the same time, the pressure of shoulder 37 on the retaining member is increased, and this increased pressure is transmitted through the compensator and the pressure plate to the snap element, whereby the curvature of the snap element is reduced until the element reaches an unstable position and finally snaps over to a position of opposite curvature, as shown in Figs. 1 and 3. During this snap action, the sides of the snap element move upwardly against the bosses 29 through a small amplitude, but the ends of the element move upwardly through a much greater amplitude. The snap movement thus produced at the ends of the element may be used to actuate a pair of independent control means, such as valves or switches, one for each end of the element.

Assuming, for example, that this snap movement is used for closing a pair of switches to supply heat to an oven, the bulb at the end of tube 42 is disposed in the oven so that the liquid in the bulb expands as the oven temperature rises. This expansion of the liquid acts to contract the bellows 39 until the end thereof engages pin 35. Thereafter, continued contraction of the bellows moves the pin 35 and the rod 34 upwardly against the action of spring 36 and thereby relieves the pressure exerted on the snap element by shoulder 37, compensator 31 and pressure plate 26. When this pressure is relieved sufficiently, the snap element moves quickly back to its initial, switch-opening position due to the permanent strain in the sheet 20 tending to return it to this position. As the oven cools, the thermo-responsive liquid contracts and allows the bellows to expand under the action of spring 36, with the result that the pin 35 and rod 34 are moved downwardly to increase the pressure on the snap element and the latter is eventually caused to snap back to its switch-closing position. Thus, the snap element moves back and forth so as to maintain a substantially constant temperature in the oven. By turning the rod 34 to different angular positions, the location of the screw 35 relative to the bellows and therefore the temperature at which the bellows operates the snap element may be varied.

The new snap mechanism is simple and compact in construction, and the component parts comprising the snap element, the pressure plate, the thermo-responsive means and compensator, and the temperature adjustment means are included in a unitary assembly. The ends of the snap element move quickly through a relatively great amplitude, and by varying the length of the snap element the amplitude may be increased or decreased. It will be observed that as the pressure plate 26 moves downwardly from the position shown in Fig. 2 to reduce the curvature of the snap element, the bosses 29 on the plate approach the seats for the snap element on the pins 24, and just as the snap action takes place the bosses engage the surface of the snap element and prevent any substantial movement of its sides between the pressure plate and the heads of the pins.

If only a single action snap mechanism is desired, the snap element shown in Fig. 11 may be employed. As there shown, the snap element is made from a relatively short piece of spring metal 44 provided with a pair of slots 45 radiat-

ing from the central part of the element toward adjacent corners thereof. The metal between the end of each slot and the adjacent corner is crimped, as shown at 46, to shorten the effective perimeter of the snap element and force it into a dished-shape. The snap element may be provided with a permanent strain so that it is self-recovering, and it may be formed near the end opposite the crimped portions 46 with an opening 47 for receiving the threaded pin 35 and with holes 48 for receiving the pins 24.

The new snap acting device is particularly adapted for use on electric ranges for operating switching means to control the temperature in the oven. In such ranges, the snap mechanism is commonly mounted adjacent the controls for the top or open heaters, and, therefore, the thermo-responsive fluid in the expansible and contractible chamber 41 may be subjected to heat from one or more of the open heaters. This extraneous heat would impair the accuracy of the oven control unless suitable provision were made to counteract its effect. In the new construction, any changes in the temperature adjacent the snap mechanism are counteracted by flexing of the compensator 31 relative to the pressure plate 26. That is, if the temperature should rise and heat the liquid in chamber 41 so as to collapse the bellows, the compensator 31 flexes and moves its ends downwardly to increase the pressure on plate 26, whereby the tendency for rod 34 to move upwardly on collapsing of the bellows is counteracted. Conversely, if the temperature adjacent the snap mechanism decreases, the compensator 31 flexes in the opposite direction and tends to relieve the pressure on the plate 26.

I claim:

1. A unitary, compensating, thermo-responsive snap acting device comprising a snap element having a dished shape, a support for the snap element engaging one face thereof, pressure and compensating members adjacent the opposite face of the snap element, said members being seated one against the other and one of the members engaging said second face of the snap element, a flexible retainer releasably secured to the support and holding said members and snap element in pressure transmitting relation on the support in a unitary assembly, whereby said members and snap element are removable from the support on release of the retainer, thermo-responsive means mounted on the support, and an adjustable connection between said means and the other of said members and extending through the support, the snap element and said members.

2. A unitary, thermo-responsive snap acting device comprising a snap element having a dished shape, a support for the snap element including a pair of headed pins projecting through the element, the heads of the pins forming seats for the snap element and engaging one face thereof at spaced points between the opposite edges of the

element, a pressure plate engaging the opposite face of the snap element and having openings for receiving the pins, a flexible retainer releasably secured to the support and holding the plate and snap element in pressure transmitting relation on the support in a unitary assembly, whereby the plate and snap element are removable from the support on release of the retainer, thermo-responsive means mounted on the support, and an adjustable connection between said means and the pressure plate and extending through the support, the snap element and the plate, said pins being operable to maintain the pressure plate, the snap element and said connection in centered relation on the support during operation of the snap element by said means.

3. A unitary, compensating, thermo-responsive snap acting device comprising a snap element having a dished shape, a support for the snap element engaging one face thereof, a pressure plate engaging the opposite face of the snap element and having its ends offset away from the snap element, a bimetallic compensator engaged at its ends with said offset ends of the plate, the intermediate portion of the compensator being free to flex relative to the plate, a flexible retainer releasably secured to the support and receiving said ends of the compensator and plate for holding the compensator, the plate and the snap element in pressure transmitting relation on the support in a unitary assembly, whereby the compensator, the plate and the snap element are removable from the support on release of the retainer, thermo-responsive means mounted on the support, and an adjustable connection between said means and the compensator and extending through the support, the snap element, the plate and the compensator.

4. A unitary, compensating, thermo-responsive snap acting device comprising a snap element having a dished shape, a support for the snap element engaging one face thereof, pressure and compensating members adjacent the opposite face of the snap element, said members having offset ends and being seated one against the other at said ends in pressure transmitting relation so that the intermediate portion of the compensating member is free to flex relative to the pressure member, one of the members engaging said second face of the snap element, a flexible, generally U-shaped retainer engaging the intermediate portion of the compensating member and having openings in its legs for receiving said ends of the compensating and pressure members, the legs being secured near their ends to the support and holding the snap element and said members on the support in a unitary assembly, thermo-responsive means mounted on the support, and an adjustable connection between said means and the central portion of the retainer and extending through the support, the snap element and said members.
